UNITED STATES PATENT OFFICE.

ROBERT GOOD, OF ROUGHKEEPSIE, NEW YORK.

JAR OR BOTTLE RECEIVER.

SPECIFICATION forming part of Letters Patent No. 508,697, dated November 14, 1893.

Application filed July 5, 1893. Serial No. 479,681. (No model.)

To all whom it may concern:

Be it known that I, ROBERT GOOD, a citizen of the United States, residing at Poughkeepsie, in the county of Dutchess and State of New York, have invented certain new and useful Improvements in Jar or Bottle Receivers; and I do hereby declare the following to be a full, clear, and exact description of the invention, such as will enable others skilled in the art to which it appertains to make and use the same.

My invention relates to devices for preserving the shape of jars, bottles and other glass vessels in finished form or as they are separated from the glass-blower's pipe, before they become cool and entirely rigid; and the objects of my invention are, first to provide a form or pocket of a diameter and shape corresponding to the glass vessel to be placed in it, and thus obviate the necessity of rolling the jar or bottle in the ordinary way; second, to arrange these pockets so that they may be conveniently moved from the position where they receive the vessel in finished form or from the blow-pipe, to a point where it may be carried to the annealing chamber in the usual way; and third, to combine with the movable jar or bottle-holder an upright T, or an equivalent cut-off blade, for severing the glass stem connecting the vessel with the blow-pipe. I attain these objects by the device illustrated in the accompanying drawings in which—

Figure 1, is a perspective view of my entire device, arranged, as is usually convenient, to rest upon the floor. Fig. 2, is a side elevation of the same, showing it as supported from above, one of the pockets, being represented in section, containing a bottle, and the other containing a jar with the blow-over as cut off from the blow-pipe; and Fig. 3, is also a side elevation of the same showing it as supported from the side by a bracket.

Similar letters refer to similar parts throughout the several views.

In the drawings A represents the tube or sleeve in which the supporting rod B, rotates and is held in place by the shoulder b, resting upon the upper end of A. Upon this movable support may be placed any desired number of forms or pockets, preferably two on each side of the central division strip D, and inclining

enough toward D to prevent the vessel from being displaced by the movement of the jar or bottle-holder. These pockets C, may be of metal or any suitable material and should be made to conform in size and shape with the glass vessels, for which they are to be used whether they be curved or angular. They are preferably constructed with interior escape openings c, at the lowest point adjoining the division strip D, to permit them to be readily freed from bits of glass and easily cleaned. The pockets may be lined with asbestos or any suitable substance to prevent the danger of cracking when the hot glass vessels are first placed in them.

The movable device as above described may be supported by the base M, the pendent N, or the bracket O, as shown in Figs. 1, 2, and 3 respectively, according to the conveniences of location and may be made to rotate vertically as well as horizontally. At the proper height and distance from the pockets C, I place a T-shaped cut-off composed of the support E and the blade F. The cut-off may be connected with the supports M or O, as shown in Figs. 1 and 3, or entirely separate as represented in Fig. 2; and it is not necessarily restricted to the T form shown.

The simple operation of my device will be readily seen by reference to Fig. 1. The glass-blower having formed his vessel of the desired size and shape, deposits it in one of the pockets C, and severs the connecting stem 85 upon F. A helper standing opposite turns the filled pocket toward himself and quickly removes the glass vessel with his fork or other implement and thus brings the empty pockets into position to be filled by the glass-blowers. 90 In the manufacture of bottles also, my device may be used to receive the bottles as they come from the finisher, for preserving their shape while hot.

Hitherto it has been necessary to provide a helper to roll upon the ordinary rolling board each jar or bottle before it is rigid enough to be safely carried by other helpers upon their forks or paddles to the annealing chamber.

It will readily be seen that my device by receiving the hot glass vessel in a pocket corresponding to it in size and form prevents any variation in shape, without the need of rolling it, and thus does away with the cost, involved

under the old method, in employing so much more labor.

Having thus described my invention, what I claim, and desire to secure by Letters Patent, is—

1. A jar or bottle receiver comprising one or more series of pockets adapted in size and form to receive and hold glass vessels, after finishing or as they come from the blow-pipe, mounted upon a support to be rotated as and for the purpose described.

2. A jar or bottle receiver comprising one or more series of pockets adapted in size and

form to receive and hold glass vessels as they come from the blow pipe, and mounted upon a support and adapted to be rotated, in combination with a cut off blade for severing the glass vessel from the blow-pipe, substantially as and for the purpose described.

In testimony whereof I affix my signature in presence of witnesses.

ROBERT GOOD.
